CLAIM

The ornamental design for a firearm grip, as shown and described.

DESCRIPTION

FIG. 1 is an isometric view of a firearm grip showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a bottom plan view thereof; and,

FIG. 7 is a top plan view thereof.

The broken lines in FIGS. 1-7 are included for the purpose of illustrating use and environment, and form no part of the claimed design.
